(57) **CLAIM**

The ornamental design for a display screen with a graphical user interface, as shown and described.

DESCRIPTION

FIG. 1 is a front view of a display screen with a graphical user interface; and,

FIG. 2 is a front view of a second embodiment thereof. The broken line showing of the text and images forms no part of the claimed design.

1 Claim, 2 Drawing Sheets

FIG. 1

FIG. 2
